Primary Examiner — Melanie H Tung*Assistant Examiner* — Bao-Yen T Nguyen(74) *Attorney, Agent, or Firm* — Kinney & Lange, P.A.(57) **CLAIM**

The ornamental design for packaging for batteries, as shown and described.

DESCRIPTION

1. Packaging for batteries

1.1 : Front

1.2 : Back

1.3 : Left

1.4 : Top

1.5 : Bottom

1.6 : Perspective

1.7 : Perspective

The right view is the same as the left view; a spacer for fixing the batteries is stored into the packaging body; at the end of the spacer, there is a circular cutout.

1 Claim, 5 Drawing Sheets(56)
